JOHN E. GILSON, OF PORT WASHINGTON, WISCONSIN.

INTERNAL-COMBUSTION ENGINE.

1,316,229.

Specification of Letters Patent. Patented Sept. 16, 1919.

Application filed April 30, 1914. Serial No. 835,373.

To all whom it may concern:

Be it known that I, JOHN E. GILSON, a citizen of the United States, and resident of Port Washington, in the county of Ozaukee 5 and State of Wisconsin, have invented new and useful Improvements in Internal-Combustion Engines, of which the following is a description, reference being had to the accompanying drawings, which are a part of 10 this specification.

This invention has for its object to provide an internal combustion engine with a novel form of magneto driving connection whereby an oscillating movement of the armature of the magneto is produced at a desired speed and at the proper time, either while the engine is running normally or when it is being started by a rack and pinion driving connection actuated by a cam on the 20 cam shaft.

Heretofore it has been found feasible to drive a magneto from the half time gear on the crank shaft at twice the speed of the crank shaft, and various means have been 25 proposed for timing the spark to correspond with the direction of turning of the engine to produce the spark at the peak of the current wave generated by the magneto and have both occur at the proper time in the 30 cycle of operation of the engine to produce the best results. On account of the usual method of starting a stationary combustion engine by reversing the direction of movement of the crank shaft after having moved 35 it in the running direction to a sufficient extent to cause an explosive charge to be drawn into the cylinder, and thus in the reverse movement produce a partial compression of the explosive charge, it is necessary 40 to produce ignition during such backward stroke of the piston, at a position of the parts different from their position at the time the spark is produced during normal running. With battery ignition it is a simple 45 matter to produce the ignition spark whenever desired, but with a gear connected magneto there are certain limitations to the timing of the spark owing to the fact that the current generated by the magneto is 50 an alternating current, and to be effective

the spark must be produced at the time of the peak of the wave of current as the magneto armature core is leaving the pole pieces of the field.

With the present invention I make use of 55 a partial revolution of the armature shaft of the magneto, just sufficient to generate one wave of current and time such operation with the operation of the sparking device so that the maximum ignition spark will be 60 produced at all times, even when starting the engine with comparatively low speed. The quick movement of the magneto armature necessary for this purpose is accomplished through a rack and pinion driving 65 connection actuated by a cam on the cam shaft of the engine.

With the above and other objects in view the invention consists in the internal combustion engine as herein claimed and all 70 equivalents.

Referring to the accompanying drawings in which like characters of reference indicate the same parts in the different views:

Figure 1 is a diagrammatic view of an internal combustion engine constructed in accordance with this invention, with the full throw of the crank shaft shown in dotted lines, and the position of the crank on producing the spark for starting the engine being shown in full lines, and the cylinder and piston being shown in dotted lines; and,

Fig. 2 is a plan view of the parts.

In these drawings 10 indicates the crank shaft of the combustion engine and 11 is 85 the crank thereof, there being a half time gear 12 on a cam shaft 13 meshing with a pinion 14 on the crank shaft 10, as usual, to drive the cam shaft at half the speed of the crank shaft. Besides having a cam 15 90 to actuate a push rod 16 of a valve mechanism 17, as usual, the cam shaft 13 also has a cam 18 engaging the roller on the end of a push rod 19 which is suitably mounted in a slide bearing 20 and is held in its engagement with the cam by a coil spring 21. A rack bar 22 is adjustably connected with the push rod 19 by means of a cam coupling 23, varying the effective length of the magneto actuating member comprising the push 100

rod 19 and the rack bar 22. The rack teeth on the outer end of the rack bar 22 mesh with the pinion 24 on the armature shaft of a magneto 25, and a flanged roller 26 supports the end of the rack bar to hold it in mesh with the pinion. The magneto is shown with a pair of notches or registration marks 27, one on the armature and the other stationary, which indicate the position of the armature at the time of the development of the peak of the current wave, and at which time it is desired to operate the sparking mechanism for producing the ignition spark.

15 The rack bar 22 carries a bracket 28 in which is pivotally mounted an igniter arm 29 having the usual lifting cam surface 30 engaging a stationary lug 31 on the ignition plate 32 of the ignition mechanism, not shown, and also having the hardened metal tooth 33 to engage the swinging finger 34 of the ignition mechanism and produce the operation thereof always at the time of the development of the peak of the current wave generated by the magneto.

19 The position of the parts for starting the engine in operation is shown in Fig. 1, the crank shaft having been turned from the full line position to the dotted line portion thereof to draw an explosive charge into the cylinder, and then having been backed to the full line position to compress the charge. The parts in this figure are shown in the position in which a slight further movement 30 of the crank shaft in the direction of its arrow will produce ignition, the tooth 33 being about ready to leave the finger 34 and permit it to snap to operate the ignition mechanism, and the registration marks 27 being nearly in their registering position, indicating the attainment of the peak of the wave of current generated thereby. Upon the explosion of the charge thus compressed the engine is started in its normal operation, and 35 then the adjusting lever 23 is thrown to the dotted line position to increase the effective length of the combined operating means consisting of the push rod 19, the rack bar 22 and the lever 29, and thereby advance the timing of the ignition to occur earlier in the cycle of operation, to comply with the requirement of advancing the spark when the engine is running at high speed, as well recognized in the art of gas engine operation.

40 The oscillation of the armature of the magneto is effective for producing a wave of current of sufficient intensity to produce ignition even at the comparatively low speed of the parts in starting the engine, and as 45 the rack bar is directly connected with the operating means for the ignition mechanism the peak of the wave of current generated will always be reached at the instant the ig-

nition mechanism is operated whether the direction of movement of the engine is reversed for starting or is the direction of normal running.

50 It is found in practice that the quick oscillation of the armature of the magneto is just as efficient for the normal operation thereof as the rotary movement when gear driven directly to the half time shaft 13, and that for starting it is more efficient because of the assured rapidity of movement thereof during the slow turning movement of the 55 crank shaft.

What I claim as new and desire to secure by Letters Patent is:

1. In an internal combustion engine having a cam shaft and a magneto, a rack bar 80 reciprocated by a cam on the cam shaft, and a pinion on the armature of the magneto meshing with the rack bar to cause the armature to oscillate.

2. In an internal combustion engine having a half time shaft, a magneto and an ignition mechanism, a reciprocating rack bar operated from the half time shaft, a pinion on the armature of the magneto meshing with the rack bar to be oscillated thereby, 90 and means on the rack bar for operating the ignition mechanism.

3. In an internal combustion engine having a cam shaft, a magneto and an ignition mechanism, a sliding rack bar having engagement with a cam on the cam shaft, a pinion on the armature of the magneto meshing with the rack bar, and means on the rack bar for operating the ignition mechanism.

4. In an internal combustion engine having a half time shaft, a magneto and an ignition mechanism, a means operated from the half time shaft for oscillating the armature of the magneto and for operating the 105 ignition mechanism, said means being adjustable for varying the timing of the production of the peak of the wave of current generated by the magneto and the simultaneous operation of the ignition mechanism.

5. In an internal combustion engine having a cam shaft, a magneto and an ignition mechanism, a spring retracted push rod having engagement with a cam on the cam shaft for reciprocation thereby, a rack bar 115 having an adjustable connection with the push rod, a pinion on the armature of the magneto meshing with the rack bar, and means carried by the rack bar for operating the ignition mechanism.

6. In an internal combustion engine having a cam shaft, a magneto and an ignition mechanism, a spring retracted push rod having engagement with a cam on the cam shaft for reciprocation thereby, a rack bar connected with the push rod, a pinion on the

armature of the magneto meshing with the rack bar whereby the armature is caused to oscillate with the reciprocations of the push rod to have its armature core separated 5 from the pole pieces to generate a wave of current flow on the outward movement of the push rod away from the cam shaft, and means carried by the rack bar for operating

the ignition mechanism on such outward movement of the push rod.

10

In testimony whereof I affix my signature in presence of two witnesses.

JOHN E. GILSON.
